UNITED STATES PATENT OFFICE.

OSCAR H. DICKE, OF ROCHESTER, NEW YORK, ASSIGNEE TO GENERAL RAILWAY SIGNAL COMPANY, OF ROCHESTER, NEW YORK.

TRAIN CONTROL.

Application filed September 20, 1923. Serial No. 663,820.

This invention relates to automatic train control systems for railways.

Among the various requirements of a suitable automatic train control system for railroads, it is considered to be expedient to provide automatic means for stopping the train absolutely at times and under certain conditions, such as upon the approach to drawbridges, crossings, and in general at those places where a stop-and-stay signal is employed according to accepted signal practice. This absolute stop control is different from the ordinary so-called automatic stop, and it is contemplated that the automatic means providing for such absolute stop will be used in conjunction with suitable means for providing the appropriate control of the train in permissive or block signal territory, preferably by enforcing restrictive speed limits. While the absolute stop in question may be obtained by the use of a derail, there are many disadvantages and objections to derails, so that it is desirable to have a separate and absolute stop control of the brakes of the train.

In one particular type of train control system, to which the present invention more particularly relates, the means communicating control influences from the trackway to the moving train is of a continuous inductive type, in which, among other things, the train must continuously find flowing in two distinct trackway circuits, including the track rails an alternating signaling current. In this type of system, three distinctive controls are obtainable, two by changing the relative phase relation of the signaling currents in the trackway circuits, and the other by cutting off one of said signaling currents. Generally speaking, for reasons familiar to those skilled in the art and to some extent pointed out hereinafter, it is found expedient to utilize all three of these controls for governing the train movement in permissive or block signal territory, leaving nothing available to give an absolute stop. The present invention relates more particularly to the provision of a fourth or additional control in such a three-control continuous inductive system, this additional control for absolute stop being obtained without additional complication and in a safe and effective manner in conformity with the continuous control principle of failure on the side of safety.

The invention also contemplates the provision of novel means for facilitating train movement under artificial speed limits, while retaining the desired vigilance on the part of the engineer. For various reasons, when it comes to applying a three-control and three-speed limit system of the continuous inductive type to the practical operating conditions on railroads, many instances are found where the speed limits or restrictions artificially and arbitrarily imposed would, if rigidly observed, result in considerable delay. In order, however, to maintain or stimulate the vigilance of the engineer, so as to obtain the combined protection afforded by the automatic train control system and that provided by the prudent engineer, it has ordinarily been considered desirable to penalize the engineer each time the arbitrary speed limits are exceeded and a brake application occurs; but, as above indicated, on account of the inaccuracies of the speed limits with respect to actual braking conditions, strict adherence to this method of maintaining vigilance tends to introduce delays.

While retaining the same theory of stimulating vigilance of the engineer by penalizing him for neglect of duty, the present invention contemplates the provision of means whereby the engineer, by making a timely application of the brakes, may exceed the speed limits arbitrarily established without penalty. More specifically, it is proposed to provide a unitary device which is responsive to the rate of deceleration of the train as well as to its actual speed of movement, so that said device will indicate or reflect what may be termed the apparent speed which represents the combined effects of the actual speed and the rate of retardation. With the aid of such a combined speed and deceleration responsive device, the system is organized, as more fully explained hereinafter, so that the artificial speed limits may be exceeded from time to time, without an automatic brake application and without penalty, provided the engineer has applied the brakes manually and the train is being safely controlled, this condition of safe retardation being determined by this device.

Other objects, purposes, and characteristic features of the invention will appear as the description thereof progresses.

In describing the invention in detail, ref-

erence will be made to the accompanying drawings, in which:—

Figure 1 illustrates in a conventional and diagrammatic manner the trackway and car-carried apparatus of a train control system embodying the present invention; and

Fig. 2 graphically illustrates the permissive speed, the actual speed the vehicle may attain providing the train is being decelerated, and the apparent speed the vehicle attains in running through a caution block when the brakes are active in signal territory, and also illustrates similar graphs of a block at the approach to an absolute stop point under stop conditions of this block.

Trackway apparatus.—In describing the particular embodiment of the invention illustrated in Fig. 1, the trackway circuits and apparatus will be first described, after which the description of the car-carried apparatus and the operation of the system will be taken up. Although the train control system embodying the present invention may be applied to any type of block signaling system, and to any type of interlocking, using either alternating or direct current track circuits, for convenience the application of the invention to a block signal system employing alternating current track circuits only has been illustrated, together with a typical block at the approach to an absolute signal in interlocking territory or the like.

The track rails 1 have been shown divided by insulating joints 2 into blocks in the usual manner. The block I, and also the adjacent end of the block H partially shown, are representative or typical of the trackway equipment and arrangement employed in block signal or permissive control territory; whereas the block J is typical of the arrangement employed at the approach to an absolute stop-and-stay signal, which for simplicity may be assumed to be the absolute home signal commonly used in interlocking territory. Since the equipment of the various blocks is substantially the same, the differences being pointed out hereinafter, the blocks I and J and the adjacent ends of the blocks H and K only have been shown, and for convenience like parts have been assigned like reference numbers with distinctive exponents. Each of the blocks is divided by insulating joints 3 into two sections, conveniently referred to as the first or rear section, and the second or advance section, respectively. The present train control system is preferably although not necessarily used with the usual fixed wayside signals, which may be either of the position light, color light or semaphore signal type and may be controlled in any approved fashion; and for convenience semaphore signals Z have been illustrated without showing their well-known circuits and control

apparatus. The energy for operating the signals, relays, etc. is derived from a suitable alternating current transmission line T.

The first or rear section of each block is provided with the usual track relay 4 normally energized by track circuit current applied to the exit end of this section. The circuit of the block I for supplying this trackway current to its rear section under clear traffic conditions ahead may be traced as follows:—Beginning at the secondary winding of the transformer 6 energized from the transmission line T, wire 7, front contact 8¹ of the track relay 4¹, wires 9¹ and 10, front contact 11 of the track relay 8¹, wire 12, track rail 1, wire 13, winding of the track relay 4, wire 14, the other track rail 1, wires 15 and 16, front contact 17¹ of the track relay 4¹, the usual limiting impedance 18, wire 19 back to the secondary winding of the transformer 6.

Under caution traffic conditions, the relative direction of flow of current in this rear section of the block I is reversed because the track relay 4¹ is then deenergized, this current flowing through the same circuit as just traced except that back contacts 20¹ and 21¹ are used instead of contacts 8¹ and 17¹.

At the midpoint of the second or advance section of each block is provided a track relay 5, which is energized under clear and caution traffic conditions by energy supplied at the exit end and entrance end, respectively, of this second section. This second section of the block I is under normal clear traffic conditions energized by current supplied to the exit end thereof by a circuit which may be traced as follows:—Beginning at the secondary winding of the transformer 6, wires 7 and 22, front contact 23¹ of the track relay 4¹, wire 24, track rail 1, wire 25, winding of the track relay 5, wire 26, the other track rail 1, wire 27, front contact 28¹ of the track relay 4¹, wire 29, the usual limiting impedance 30, wires 31 and 19 back to the secondary winding of the transformer 6.

Under caution traffic conditions of the block I, this second section of the block is provided with track circuit current from the entrance end through the following circuit:—Beginning at the secondary winding of the transformer 6, wires 7 and 22, back contact 32¹ of the track relay 4¹, wire 33, the rail 1, wire 25, winding of the track relay 5, wire 26, the other rail 1, wire 34, back contact 35¹, wire 29, limiting impedance 30, wires 31 and 19 back to the transformer 6.

By looking at block I of the drawings, it will be noted that track or loop circuit current is supplied to the two sections of the trackway in a manner so as to flow in a normal direction under clear traffic conditions

of the block J, and that the first section of the block I has its current reversed if the block J is occupied, and that the second section of the block I has current supplied thereto by being fed from the entrance end of this section when the next block in advance (block J) is occupied.

Both of the sections of the block I are provided with means for supplying simplex circuit current, that is, current flowing in the two rails in multiple; and for reasons heretofore mentioned, this simplex circuit current is continuously supplied to both sections of this block regardless of traffic conditions ahead, by a transformer 69 having its secondary winding connected to the midpoints of balancing resistances 36 and 37, respectively, and a transformer 79 having its secondary winding connected to the midpoints of balancing resistances 38 and 39, respectively, so that current is supplied flowing through the two rails in multiple in each of these sections of the block I, this current dividing substantially equally between the two rails.

On account of the inductance of the track rails and the track circuit impedance, the track or loop circuit current lags considerably behind the voltage of the source of alternating current supplied over the transmission line T; whereas the current supplied to the simplex circuits is a resistive or power current, and is substantially in phase with the voltage producing it. In other words, the track or loop circuit current lags substantially 90 electrical degrees behind the simplex circuit current, this being desirable for reasons more clearly described hereinafter. These track circuit currents may be brought into quadrature by any other means, for instance, a polyphase current may be transmitted along the right of way, if desired, or any other suitable means may be employed to bring these currents into the proper phase relation.

The block J, which is assumed to be a block in the rear of a home signal in interlocking territory, is in many respects similar to the block I in block signal territory. The main difference between the block I and the block J is that the various contacts for controlling the loop circuit current to the block J are controlled by a line relay 40 instead of the track relay 4², and that the insulating joints 2 of the blocks are located a considerable distance beyond the signals Z², this section between the signal and the insulating joint at the end of the block being provided with a controllable simplex circuit comprising balancing resistances 41 and 42, which may be supplied with energy at their midpoints by two distinctive circuits which may be traced as follows:—Beginning at the secondary winding of the transformer 43, wires 44 and 45, front contact 46 of the line

relay 40, wires 47 and 48 to the midpoint of balancing resistance 42, thence over the track rails to the midpoint of balancing resistance 41, wires 49, 50 and 51 back to the secondary winding of the transformer 43; and a circuit beginning at the secondary winding of the transformer 43, wires 44 and 52, contact on the usual interlocking lever 53 in the tower 54, which lever is interlocked with levers of conflicting routes so that it can only be operated when it is proper to do so, wires 55 and 56, the call-on push button 57 also located in the signal tower 54 conventionally shown by a dotted rectangle, wires 58 and 48, balancing resistance 42, the two track rails in multiple, balancing resistance 41, wires 49, 50 and 51 back to the secondary winding of the transformer 43.

The line relay 40 is normally energized by the following circuit, which is closed when both the block in advance is unoccupied and the lever 53 in the tower 54 is placed in its clear position:—Beginning at the secondary winding of the transformer 43, wires 51 and 60, front contact 61 of the track relay 4², wire 62, winding of the line relay 40, wires 63 and 55, contact of the usual interlocking lever 53 located in the tower 54, wires 52 and 44 back to the secondary winding of the transformer 43.

On the same signal pole with the absolute stop-and-stay signal Z² is provided a "call-on" signal, which is intended to be used in accordance with recognized practice to call-on the engineer or to advise him that he may proceed regardless of the fact that the stop-and-stay signal is at stop, as, for example, when it is desired to allow the second section of a train to follow closely behind the first section into such interlocking territory. This call-on signal is normally in the inclined non-indicating position as shown, and is placed in a vertical position when the following circuit is energized:—Beginning at the secondary winding of the transformer 43, wires 44 and 52, contact of the interlocking lever 53 in the tower, wires 55 and 56, call-on push button contact 64, wire 65, control mechanism of the call-on signal 59, wires 66, 50 and 51 back to the secondary winding of the transformer 43.

By referring to the block J, it will be noted that the loop circuit current for this block may be controlled automatically by the track relay 4² in the same manner as the current is controlled in the block I, and that the block J may be put in its caution traffic condition by moving the lever 53 in the tower 54 into its dotted position. Also, it will be noted that if the block J is in its caution condition, either because the track relay 4² is deenergized or because the lever 53 is in its dotted position, the simplex circuit including the balancing resistances 41 and 42 is deenergized, and that an absolute

stop is inflicted if a train passes the signal Z^2 because of the absence of this simplex current, by reason of suitable car-carried apparatus to be described hereinafter. Also, 5 it will be noted that if the block K is occupied by another train and the tower man wishes a train moving in the block J to pass into the block K, he may place the lever 53 in the clear position, as shown in the drawing, 10 which will avail him nothing for the reason that the simplex circuit beyond the signal Z^2 is still deenergized, because the front contact 46 of the line relay 40 is in its lower position; and in order to permit the 15 train to proceed, he must push the push button 67 whereby the arm of the call-on signal assumes its clear position and the simplex circuit is energized so that the train may proceed regardless of the condition of the 20 track relay 4.

From the foregoing it can be readily seen that, in block signal territory, represented by the block I, each block is divided by insulated joints 3 into two sections, the track 25 rails of both of these sections being continuously and at all times irrespective of traffic conditions supplied with simplex current flowing in the same direction in the track rails at any given instant. The loop or 30 track circuit current for the first or rear section of each block is controlled, first as to continuity by the relay 5 of the second or advance section of the same block, and second as to polarity or relative phase relation 35 by the track relay of the block next in advance. The loop or track circuit current for the second or advance section of each block is normally and under clear traffic 40 conditions connected across the track rails at the exit end of that section, which is also the exit end of the block itself, and is shifted to a connection across the entrance end of this section under caution traffic conditions, that is, when the next block in 45 advance is occupied.

In interlocking territory, or at points where an absolute stop control is desired, the block, represented by the block J, in addition to the two sections arranged and 50 controlled the same as in block signal territory, is provided with a short section as regards simplex current, although no insulated joints are employed, and the supply of simplex current to this short section at 55 the end of the block and just beyond the home signal, is separately controlled so as to provide an absolute stop when required. In other words, the block for a home signal or other absolute control point has in effect 60 three sections or portions, two of which are energized and controlled in the same way as in block signal territory, and the other of which is separately and ordinarily manually controlled to give an absolute stop whenever required.

It should be understood that the arrangement of the call-on signal and its particular manner of control illustrated is of course optional and susceptible of modification or adaptation in conformity with established 70 interlocking practice; and it should also be understood that the trackway equipment and arrangement of circuits shown is diagrammatic and illustrative, and is not intended to include the various refinements, 75 additions, or adaptations, that would be adopted in practice in applying the invention to the varying conditions encountered on railroads.

Car-carried apparatus.—For convenience a 80 railway vehicle has been conventionally illustrated by showing the first and a subsequent axle 70 and 71, respectively, of an engine and tender unit, or car of a multiple unit electric train, depending upon the type 85 of train to which the train control system embodying the present system is applied. Carried on the vehicle directly in front of the first axle 70 are two suitable influence detecting or receiving elements LE for detecting 90 the flow of alternating current flowing in the loop circuit on the trackway. These loop circuit receiving elements LE each comprise a core 72 of suitable magnetic material, preferably laminated, insulated between lamina and supported a suitable distance above the track rails so as to afford the proper clearance. This core 72 of each of these elements has depending legs terminating in 95 pole pieces 73, and is provided with a coil 100 74. The coils 74 of the two receiving elements LE are connected in series in a manner so that current flowing in one direction in one rail through the axle of the vehicle and back in the other direction in the other 105 rail will induce electro-motive-forces in the coils 74 which are cumulative.

Similarly, a simplex influence receiving element SE for detecting simplex current flowing through the two rails in multiple is 110 carried on the vehicle in the rear of the axle 71. This element SE comprises a similar but longer core 75 having depending legs terminating in pole pieces 76, and provided with a winding 77 in which electro-motive-forces are induced due to current flowing in 115 the same direction in the two rails in multiple.

The loop circuit current influence detecting element LE is connected to a loop circuit amplifying device, which has been conventionally illustrated by a square AL. This amplifying device AL has its output wires connected to the winding 80 of a two-element relay CR through the front contact 81 of a reset and penalizing switch, more fully described hereinafter, through a circuit which may be readily traced in the drawings. This amplifying device is designed so that currents flowing in the loop circuit ahead of the 120 125 130

train are reproduced, amplified, and applied without change in phase to the winding 80 of the control relay CR.

The winding 77 of the simplex influence 5 receiving element SE is connected to an amplifying device conventionally shown by a square and designated AS. The output circuit of this simplex amplifying device AS is connected to the other winding 82 of the control relay CR, and also to the winding of 10 the stop relay S in a manner as shown in the drawings. These amplifying devices AL and AS include the usual vacuum tube or thermionic amplifiers, coupling units, and 15 the necessary tuning apparatus and sources of energy, all as well understood by those skilled in the art of thermionic radio communication.

In order to inform the engineer of the 20 positions of the control relay CR, and in turn the conditions of traffic ahead of the train, suitable signals are preferably provided at a convenient place in the cab for giving such information. For convenience, such signals 25 have been conventionally shown by four lamps colored green, yellow, red and orange respectively, and designated G, Y, R and O, respectively. These lamps are at times energized by being connected across the terminals B and C respectively of a suitable vehicle carried source of energy by circuits readily traced in the drawings. These circuits maintain the green lamp G energized when traffic conditions ahead are clear and 30 the relay CR is in its normal position; maintain the yellow lamp Y energized when traffic conditions are caution and the relay CR is in its reverse position; maintain the red lamp R energized when the relay CR is deenergized corresponding to danger traffic conditions ahead; and maintain both the red and the orange lamp energized when an absolute stop is being enforced and the stop relay S assumes its deenergized position.

In order to manifest on the train that it 45 is being slowed down properly in a caution block in response to a manual application of the brakes, as well as the running speed of the vehicle, a suitable combined centrifugal 50 speed responsive device and decelerating device has been provided, which may for convenience be referred to as an apparent speed indicator. This apparent speed indicator AG consists of the essential elements of a 55 centrifugal speed responsive device and means for modifying the indication of this device in accordance with deceleration of the train.

More specifically, this apparent speed indicator AG comprises a shaft 85 mechanically connected and driven by one of the axles of the railway vehicle by suitable means to rotate it in the same direction (in the particular arrangement shown, this direction being anti-clockwise as indicated by

the arrow), regardless of the direction of movement of the train, that is, regardless of whether it is moving pilot or tender first. From the shaft 85 projects a radially extending pin 86 engaging a helical slot 87 in 70 a sleeve 88 surrounding and loose on the shaft 85. This sleeve 88 has ears 88^a extending therefrom to which are pivotally secured links 90 having their free ends connected to centrifugal weights 91. The 75 sleeve 88 is held in its normal position shown by a torsion spring 92 contained on the shaft 85, having one end fastened to the shaft by a pin 93, and having its other end secured to the sleeve 88 by a screw 94. On 80 the shaft 85 above the sleeve 88 is supported another sleeve 95 having similar ears 95^a to which are pivotally secured links 97, having their free ends pivotally connected to the centrifugal weights 91. On the shaft 85, 85 between the sleeves 88 and 95, is a compression coil spring 98 which urges these sleeves apart, so that the weights 91 closely approach each other while the shaft 85 is at rest. To the sleeve 95 is fastened but insulated therefrom a grooved collar 99, in the groove of which extends the bifurcated end of an indicating arm 100 pivotally supported by a pin 101.

Upon consideration of this structure of 95 the apparent speed indicating device AG, it will be noted that, if the shaft 85 is rotating at a constant speed, the speed indicating arm 100 will move about its pivot to a position corresponding to the speed of the shaft 85 100 by the action of centrifugal force upon the weights 91 in the usual manner, and also that if the shaft 85 is rotating at a constant speed or is accelerating the pin 86 will engage the end of the slot 87 (as shown) so that the 105 sleeve 88 maintains the same relative position with respect to the shaft 85 as it does when at rest and the speed of the train is accurately indicated by the speed arm 100. However, if the shaft after having been 110 running at a certain speed is retarded or decelerated, the inertia of the weights 91 causes these weights and the sleeves 88 and 95 to be positioned a certain angle ahead or slightly in advance of the shaft 85. While 115 the sleeve 88 and the weights 91 are positively driven at the same rate as the shaft 85 so long as this shaft is accelerating or rotating at a constant speed, whenever this shaft decelerates or slows down, the slot 87 120 permits the sleeve 88 and the connected parts to move relatively with respect to the shaft, this relative movement being opposed by the spring 92. On account of the shape and angularity of the slot 87, this relative 125 movement of the sleeve 88 with respect to the shaft 85 forces the whole centrifugal device endwise on the shaft 85, changing the position of the arm 100, the same as if the speed of rotation of the shaft 85 were lower 130

and the centrifugal weights 91 were not so far out. It will be evident that, by properly proportioning the spring 92 and shape of the cam slot 87, with due regard to the various forces involved, the position assumed by the arm 100 while the train is being decelerated by its brakes and the shaft 85 is slowing down, may be made to reflect the combined effect of the actual speed of rotation of the shaft 85 and its rate of deceleration to any desired degree or relationship. In the particular embodiment of the invention illustrated, the apparatus is preferably designed so that the deceleration that ordinarily takes place when a train is being braked by a full service application will cause the speed arm 100 to indicate an apparent speed, which is substantially 20 miles per hour less than the actual running speed of the vehicle, for reasons more clearly described hereinafter.

The speed indicating arm 100 is adapted to move over contacts 102, 103 and 104, respectively, which are of such length that they are in contact with this speed arm 100 if the train is moving at the rate of less than 20, 40 or 60 miles per hour, respectively. These specific speed limits are chosen for the purpose of illustration only, and may be departed from in practice, if desired. These contacts 104, 103 and 102 are connected to the terminal B of a source of energy when the stop relay S is energized and the control relay CR is energized in the normal 35 position, in the reverse position or is deenergized, respectively.

In order to automatically apply the brakes of the usual air-brake system, a suitable application valve diagrammatically illustrated 40 and designated AV has been shown. This application valve is connected to the main reservoir MR, the brake pipe BP, atmosphere AT, to the usual engineer's brake valve EV and to an equalizing reservoir and a reduction reservoir ER and RR, respectively. This application valve is preferably designed to automatically vent the brake pipe to a predetermined extent when actuated, and to cut off main reservoir pressure from the 50 engineer's brake valve so that the engineer may not prevent an automatic brake application by placing the usual engineer's brake valve into the release position to recharge the brake pipe. Since this application 55 only forms an element in the present system, it has not been specifically shown and described; and for a specific disclosure thereof, attention is directed to the co-pending application Ser. No. 596,102, filed October 21, 1922, by Charles S. Bushnell.

This application valve AV is constructed so that if air is vented from the pipe 105, the valve is actuated and automatically applies the brakes in the manner above described.

65 This pipe 105 is connected to an electro-

pneumatic valve EPV, which maintains this pipe closed when the device EPV is energized but connects it to atmosphere if it is deenergized. The device EPV may be constructed in any suitable manner so as to function as just described. This electro-pneumatic valve EPV is also provided with a front contact 106 closed when the device is in its energized position. This device EPV is normally energized, that is, is energized 75 when the indicating arm 100 is connected to the terminal B of a source of energy. The circuit for energizing this device EPV may be traced as follows:—Beginning at the indicating arm 100, which, under predetermined traffic conditions, is connected to the terminal B of a battery through the contact 68 and one of the contact strips 102, 103 and 104, wire 107, winding 108 of the device EPV, wires 109 and 110, front contact 106, wire 111 back to the other terminal 85 C of said source of energy. It is thus noted that the device EPV is connected in a stick circuit which if momentarily deenergized will prevent reenergization of the device, 90 because its energizing circuit is broken by its own front contact.

Another element of the car equipment is the reset switch RS which has to be operated to permit the brakes to be released and the train to proceed after default by the engineer and an automatic application of the brakes has occurred. This reset switch RS is shown diagrammatically as a simple switch or push button having normally open contacts and normally closed contacts mechanically connected and simultaneously operated. The normally open contacts are for performing the resetting function, while the normally closed contacts are for protecting 100 the reset switch against misuse.

As indicated by the dotted rectangle, this reset switch RS in practice is preferably enclosed in a suitable protecting box or casing so mounted on the locomotive or other vehicle that it can be reached only by a person standing on the ground. In other words, the reset switch RS is accessible only from the ground, and the train must be stopped before the switch can be operated. If desired, 110 a suitable recorder or counter may be used with the switch to make a permanent record of the number of times it is operated; or, the enclosing box may be locked and the key held by the conductor, or the box may be sealed or some other expedient adopted to assure report each time said switch is operated, so as to give the officials information about the care and vigilance of the various 115 engineers. It should be understood that the provision of such a reset switch, accessible only from the ground, as the means for penalizing the engineer is merely illustrative of a suitable penalizing means, and other arrangements for inflicting a penalty may be 120 125 130

employed so far as the fundamental functions and attributes of the system are concerned.

In an automatic train control system of the continuous inductive type provided with means constructed in accordance with this invention for producing an absolute stop, if a failure of trackway energy should occur for any reason, or a simplex circuit along the trackway should be interrupted, the train would be brought to a stop and could not proceed. In order to allow the train to proceed at all under such conditions, a suitable emergency cutout device has been provided, which comprises a valve 112 connected in the pipe 105 between the device EPV and the application valve AV, so that if the engineer closes this valve 112, the application valve will not be actuated regardless of the condition of the device EPV. In order to prevent the engineer from maliciously placing this valve in the cut-off position so as to avoid the automatic application of the brakes and the resulting penalty, this cutout device is normally placed in its ineffective position and maintained in this position by a seal 113. If for any reason the engineer is unable to proceed at a point along the trackway where he should be permitted to proceed, he may break this seal 113 for which he will be excused under such conditions. If, however, the seal is broken at a time when both the trackway and car-carried apparatus are in working order, the engineer could be severely criticized and probably discharged for breaking the seal under these conditions.

OPERATION OF THE SYSTEM.

Speed control and block signal territory.—While the train is running under clear signals in a clear block, the loop circuit current for the first or rear section of the block is of normal polarity, and that for the second or advance section is of normal polarity and is fed from the exit end of the block. The simplex circuit current, as already pointed out, is always present in both sections of the blocks in block signal territory. Consequently, both field windings 80 and 82 of the relay CR are energized by the amplified energy induced in the receiving elements LE and CE by this loop circuit and simplex circuit current. Also, energy is supplied to the stop relay S, maintaining its contact finger or armature in the upper position shown.

With the relay CR in the normal position shown, the green light G is illuminated, and the long or maximum speed contact strip 104 is included in the circuit for the electro-pneumatic valve EPV. The train may travel at any speed less than the maximum speed for which the apparatus is designed, say 60 miles per hour. If this maximum

speed limit is exceeded at any time, the arm 100 leaves contact with the strip 104 and breaks the energizing circuit for the electro-pneumatic valve EPV, which opens and applies the brakes automatically through the agency of the application valve AV. As soon as the electro-pneumatic valve EPV is deenergized, its front or stick contact 106 opens, so that irrespective of subsequent reduction in speed and engagement of the arm 100 with the strip 104, said electro-pneumatic valve can not be re-energized. In other words, whenever the maximum speed is exceeded, the brakes are applied and held applied until the electro-pneumatic valve is independently restored by the reset switch RS.

To reset the electro-pneumatic valve EPV after automatic operation thereof, the train must be brought to a stop and the reset switch RS operated, closing its open contacts and opening its closed contacts. The closure of the open contacts 121 of the reset switch RS establishes, together with wire 120, a multiple or shunt connection to the terminal of the battery designated C in lieu of that through the contacts 106 of the electro-pneumatic valve, so that with the circuit of this valve closed at some one of the strips 102, 103 and 104, the valve is re-energized and after such energization is maintained energized by its normal circuits.

It will be noted that the normally closed contacts 81 of the reset switch RS are included in the circuit for the field coil 80 of the relay CR, so that with the reset switch operated, the field coil 80 is deenergized regardless of the presence of loop circuit current and the relay CR is deenergized, limiting the speed to the minimum speed. In other words, so long as the reset switch RS is held in its operated or resetting condition, the train can not proceed above the minimum speed. This assures that the reset switch RS will not be maliciously or carelessly left or fastened in the wrong position, but will be restored after each operation thereof.

For reasons explained more in detail hereinafter, the engineer may avoid the automatic brake application and the resulting penalty upon exceeding the maximum speed limit by having the brakes applied. This is helpful for the engineer in handling his train under unfavorable conditions where it is difficult to avoid temporarily exceeding the maximum speed limit. Adequate safety is assured, however, by reason of the fact that the prevention of automatic braking and the suppression of the penalty is effective only so long as the brakes are applied; and so far as safety is concerned, it is not material whether the train is being slowed down due to a manual application of the brakes already in effect, or by an automatic brake application initiated by exceeding the artificial speed limit.

Speed control in a caution block.—When the train enters a caution block, that is, a block next in the rear of a block in a dangerous condition due to the presence of another train or otherwise, it is necessary to assure regulation of the speed of the following train in such a fashion that it will be brought to a stop, or to a predetermined minimum speed, before reaching the end 10 of the block. In other words, the beginning of the next block in advance is taken to be the point of danger, and the train in the caution block is controlled so as to stop, or be brought down to a safe low speed, before reaching the point of danger.

According to this invention, the desired control of the speed in a caution block is obtained by setting up in succession an intermediate speed limit and a minimum speed limit. While other well-known expedients may be employed, the change from the maximum speed limit for clear traffic conditions to the intermediate speed limit is made abruptly, and likewise that from the intermediate speed limit to the minimum speed limit. These changes in speed limit are made instantly in response to the operation of the control relay CR.

Explaining this control in a caution block in detail, let us assume that the train shown has its car-carried apparatus in the normal condition as shown and is moving in the block H in the normal direction of traffic, as indicated by the arrow, when the block J is occupied by another train. With the block J occupied by another train, the track relay ⁴¹ assumes its deenergized position and reverses the relative polarity of the loop circuit current in the first or rear section of the block I and transfers the track feed of the second or advance section of the block I from the exit end to the entrance end thereof in the manner heretofore explained. As the vehicle moves into the block I, the control relay CR assumes its reverse energized position because of the reversal of the loop circuit current, thereby illuminating the yellow lamp Y and supplying energy to the contact strip 103, instead of the contact strip 104, of the apparent speed indicating device. Since the contact strip 104 is no longer connected to the terminal B of the source of energy but the contact strip 103 is so connected, if the speed of the train is above, say 40 miles per hour so that the arm 100 is not in contact with the strip 103, it is necessary for the engineer to take appropriate action so as to bring the indicating arm 100 into contact with the strip 103 in order to avoid an automatic brake application and the resulting penalty.

In Fig. 2 has been illustrated graphically how the engineer may accomplish this result, although his speed just before entering

the block is the maximum speed permitted, namely, 60 miles per hour. The curves illustrated in Fig. 2 show the actual, the permissive and the apparent speed when the train is being brought to a low speed in a caution block as the result of a manual brake application, the solid line 116 indicating the actual speed of the vehicle, the dotted line 117 indicating the permissive speed, and the dot and dash line 118 indicating the apparent speed the train is traveling, as indicated by the arm 100 of the apparent speed indicating device.

In order to prevent an automatic brake application and the infliction of a penalty, the engineer must either travel at a speed of less than 40 miles per hour or he must apply the brakes so that an adequate brake application is effected before reaching the entrance to the block I. As soon as the brakes become active and deceleration of the vehicle takes place, the decelerating device, forming part of the apparent speed indicating device AG, begins to function causing the sleeve 88 to make a partial rotation with respect to the shaft 85 in the direction of the arrow to cause the indicating arm to indicate the actual speed minus a component, depending on deceleration. The dot and dash curve 118 illustrates how the apparent speed drops down very abruptly as the brakes become active, thus bringing the indicating arm 100 on the contact segment 103 before the block I is entered. If the engineer keeps the brakes applied, the apparent speed will decrease at substantially the same rate as the actual speed, indicated by the curve 116 in Fig. 2, decreases with the brakes applied. The engineer is obliged to keep the brakes applied until the actual speed of the train is below the permissive speed limit, that is, until the speed of the train, assumed to be about 60 miles per hour at the start, has been reduced below the 40 mile per hour permissive speed limit indicated by the dotted line 117. If the engineer should release the brakes, the deceleration of the shaft 85 at once ceases and the spring 92 acts to bring the sleeve 88 around to its normal position, thereby raising the upper sleeve and shifting the arm 100 to the position corresponding to the actual running speed of the train, with the result that, if this actual speed is greater than the permissive speed limit, the arm moves out of contact with the strip 103 and the electro-pneumatic valve EPV is deenergized, automatically applying the brakes and requiring a reset from the ground as a penalty.

In the foregoing explanation, it was assumed that the train entered the caution block at nearly the maximum permissible speed, requiring the engineer to make a full service application to avoid an automatic brake application and a resulting penalty.

It may happen, however, that the train enters the caution block in question at a speed somewhat lower than the maximum speed but still higher than the intermediate permissive speed limit put into effect upon reversal of the relay CR. Under these conditions, while an application of the brakes to some degree is necessary for safety, on account of the lower speed it is not essential that a full service application should be made. This situation is taken care of according to this invention by reason of the fact that, the less the actual speed of the train is above the permissive speed limit, the less the intensity of the brake application and the amount of deceleration necessary to move the arm into contact with the strip 103. Accordingly, the engineer of a train entering a caution block at a moderate speed may, if he desires, avoid the automatic application and penalty by making a partial service application, sufficient to bring the speed down to the intermediate speed limit at the proper point. The engineer may, of course, make a full service application upon entering each caution block, regardless of how much the actual speed is above the intermediate speed limit; but as soon as the actual speed has been brought below the permissive speed limit, the engineer may release the brakes and proceed at a little less than this permissive speed limit. It may be explained here that a full service application has been mentioned in the foregoing explanation on the assumption that the block lengths or at least the points where the intermediate speed limit is put into force will, in the interests of track capacity, be based on stopping the train with a full service application. This, however, is obviously optional. It should also be understood that the first or rear section of the block may be longer than necessary to bring the train from its maximum speed to the intermediate speed limit, with the result that the braking curve 116 and the permissive speed limit line 117 will cross at some point in the rear of the insulated joints 3. This is particularly true in case of long blocks, although in this case special expedients not herein disclosed may be employed, if desired, to cause the intermediate speed limit to be effective at some distance in advance of the physical entrance to the block, rather than at the entrance thereto. In short, the particular curves illustrated and the foregoing discussion are predicated upon certain assumed conditions which need not be followed and which ordinarily are variable in the application of the system to practical operating conditions. In order to avoid complication, however, these various refinements, exceptions, and adaptations to the simple and fundamental application of the invention will not be analyzed and discussed.

As the train reaches the insulating joints 3 of the block I, the car-carried equipment is wholly deprived of loop circuit current ahead of the train, because the loop circuit current of this advance section is fed to the rails from the entrance end thereof, and is shunted by the axles of the train so that it is unable to reach the influence receiving elements LE at the front of the train. This causes the relay CR to assume its deenergized position, thereby cutting energy off of the contact segment 103 and applying it to the contact segment 102, thereby setting up a minimum speed limit for the train of, say, 20 miles per hour. As shown by the curves in Fig. 2, the apparent speed of the train in the block I at the entrance to the second section of this block is just a little less than 20 miles per hour while it is being decelerated, and therefore no automatic brake application will take place if the engineer maintains the brakes applied. As soon as the actual speed of the train comes below the speed limit of 20 miles per hour, the engineer may release the brakes without penalty. Upon release of the brakes, the deceleration of the train ceases and the apparent speed device indicates the actual speed instead of the apparent speed, as shown by the abrupt rise in the dot and dash curve 118 at the end of the block I.

Release in a caution block.—If, while the train in question is in the rear or first section of the block I, the train ahead leaves the block J, the track relay 4¹ picks up, and the normal polarity of loop circuit current is applied to the track rails of the block I, restoring the control relay CR to the normal position corresponding to a clear block. This restoration of the relay CR changes the cab signals from yellow to green and the speed limit from the intermediate to the maximum in an obvious manner. If the train in question should happen to be in the second or advance section of the block I at the time the block J clears up, the picking up of the track relay 4¹ which acts to shift the loop circuit feed from the rear or entrance of this section to the advance or exit end, changing the feed such that this loop circuit current may be detected by the receiving elements LE, whereby the control relay CR is restored to normal with the results above indicated.

Minimum speed in an occupied block.—As previously explained, a train is compelled to reduce its speed to a minimum speed while traveling through a caution block, this minimum speed existing on account of absence of loop circuit current in the second or advance section of such caution block and the deenergized condition of the control relay CR. If a train, having been brought down to a minimum speed in this manner, continues on and enters the danger or occu-

pied block, the same minimum speed limit is maintained in effect. This is due to the fact that a train in an occupied or danger block can not pick up any loop circuit current and the control relay CR remains de-energized, this being true whether the dangerous condition of the block is due to the presence of another train or a broken rail, or the like.

10 Considering the situation in detail, assume a train in the first or rear section of the block J and a following train, after having had its speed reduced while traveling through the caution block I, enters into this 15 rear section of the block J. The following train will not pick up any loop circuit current, because this current, if present, is all shunted out or diverted by the wheels and axles of the forward train. If a train is in 20 the second or advance section of the block J and a following train enters into said block, no loop circuit current is supplied to the following train, because the relay 5¹ is deenergized and has opened the circuit by 25 which loop circuit current is supplied. If the following train should continue and enter into the advance section of the block J directly behind said another train, still it would not receive any loop circuit current, 30 because in one instance, if the loop circuit current were fed from ahead at the exit end of the block J (block K clear), the forward train would shunt out this current, and in the other instance (block K occupied), the 35 feed of the loop circuit of the section in question would be from the rear and would not affect the receiving elements LE on the following train.

40 Thus, irrespective of the location of a train in a block, whether in the rear or in the advance section, a following train is restricted to a minimum speed throughout its travel and approach to the forward train.

45 *Release from minimum speed limit in an occupied block.*—Under certain circumstances, a train may enter an occupied or danger block which shortly after such entrance clears up, that is, the train ahead has advanced out of that block or the other 50 condition constituting danger has been removed. Under these conditions, it is safe and desirable to remove the minimum speed restriction and substitute a higher speed limit, permitting the train to accelerate, yet 55 keeping it under control and assuring that it shall be stopped or brought to a low speed by the time it reaches the end of that block, provided the next block in advance continues to be occupied. In short, upon change of a 60 danger or occupied block to a caution block, it is desirable to remove the minimum speed limit and substitute the intermediate speed limit, if the train is far enough back, or 65 retain the minimum speed limit, the same as in a caution block.

All of this is taken care of in the present invention. First, assume that the following train is in the first or rear section at the time the train ahead in the same block advances or the dangerous condition is removed, and the block changes from a danger block to a caution block. In this case, the loop circuit current is re-applied and transmitted to the following train. The polarity of this loop circuit current will be 75 reversed, if the block next in advance is occupied, and the relay CR will pick up from its deenergized position to the reverse or caution position, establishing the intermediate speed limit. This speed limit is safe 80 and proper under these conditions, because the following train in question has not yet reached the insulated joints 3 and has braking distance for this intermediate speed limit available. If, however, the train is in the 85 second or advance section at the time the block changes from danger to caution, the minimum speed limit is maintained, and properly so, because there may not be braking distance available to stop the train from 90 any higher speed limit before reaching the end of the block. It will be evident that, if a danger block changes to a clear block, the minimum speed limit is removed and the maximum clear speed limit is substituted. 95

Absolute stop.—The block J is intended to represent a typical instance of enforced speed reduction followed by an absolute stop to enforce the proper recognition to the home and distant signals of an interlocking 100 plant. In addition, the block J is provided with the same control as in block signal territory, so that trains traveling through this block are at times under control as in block signal territory, that is, under the control 105 of trains ahead, and at other times are under the manual control characteristic of an interlocking system. The features of speed control in block signal territory heretofore discussed in connection with the block 110 J apply to the block J and need not be repeated. The only difference is that the control 115 of the loop circuits for the two sections of the block J is accomplished by a line relay 40, controlled, among other things, by the track relay 4² of the next block K in advance, rather than by the track relay directly.

120 Referring now to the way in which absolute and unpreventable brake application irrespective of speed is given whenever the train passes the absolute signal Z² at stop, it will be noted that the section of track in the block J, between the signal Z² and the insulated joints 2 marking the physical end 125 of this block, is supplied with simplex circuit current under special control. If this simplex circuit current is cut off, the stop relay S on the car is de-energized, dropping its armature 119 and opening the circuit of 130

the electro-pneumatic valve EPV irrespective of speed. Also, the reset switch RS is incapable of energizing the electro-pneumatic valve EPV with the stop relay S deenergized. In short, the deenergization of the stop relay S results in a brake application which is given irrespective of speed and is maintained in spite of any attempts of the engineer to release, with the exception of 10 course of the emergency cutout valve 112.

Explaining the situation more in detail, assume that the tower man has set up a route in interlocking territory, of which the block J is a part, and that this route set up 15 conflicts with the route through the block J. This will have been done by the tower man in the usual way in accordance with well-known practice in interlocking, the lever controlling the signal Z^2 , shown conventionally as the switch 53, having been placed in the normal or stop position (shown in dotted lines), thereby breaking the energizing circuit for the line relay 40. The deenergization of the line relay 40 reverses the loop 20 circuit current to the first or rear section of the block J, between the resistances 36¹ and 37¹, and shifts the feed of the loop circuit current for the second or advance section of the block J from the exit to the entrance end 25 thereof, thereby rendering this block J the equivalent of a caution block so as to enforce speed restrictions through it in the same way as previously explained. The deenergization of the relay 40 furthermore breaks at its 30 front contact 46 the circuits supplying simplex current to the short section between the resistances 41 and 42, leaving this section just in advance of the signal Z^2 without any simplex current. It may be explained 35 here that this section just in advance of the signal Z^2 will in practice be relatively short, being preferably merely long enough to bring the train to a stop within the limits from the minimum speed at which the train may 40 enter said section, here assumed to be 20 miles per hour.

With the trackway conditions set up as just described, a train approaching the block J first receives a caution indication at the 45 signal Z^1 , corresponding to the distant indication for the home signal Z^2 , and this train is obliged to reduce its speed to a minimum during its progress through the block J. As shown by the curve 116 just below the trackway, the speed limits imposed are preferably laid out so that a train observing them 50 may come to a stop before reaching the signal Z^2 , rather than before reaching the actual exit end of the block defined by the joints 2. In other words, it is contemplated that the train under this caution control will 55 pull up to the signal Z^2 . The signal Z^2 has of course a distinctive aspect, by virtue of the shape of its blade, marker light combination, or otherwise, so that the engineer is 60 able to recognize that at this point he is obliged to stop his train and wait, instead of proceeding at a minimum speed as he may do in the case of a permissive stop signal in block territory. Strict obedience to the indication of this stop-and-stay signal Z^2 is 65 automatically enforced, because if the train should move by the signal, the stop relay is instantly deenergized, the brakes applied, and the train brought to a stop. Since the 70 reset switch RS is ineffective with the stop relay S deenergized, the brakes can not be released and the train proceed until simplex circuit current is again applied to the short section between the resistances 41 and 42, except of course by the use of the emergency cut out valve 112.

It will thus be apparent that this invention provides, in addition to appropriate speed control in block signal territory, an absolute and positive stop control, preventing a train proceeding at any speed beyond a predetermined point. Also, this absolute stop control is obtained in conformity with the continuous inductive control principle, 80 and utilizes a large part of the apparatus used for control in block signal territory. Such automatic and absolute stop control, therefore, serves the function of a derail and positively prevents train movement beyond a certain point and prohibits a train moving at any speed on to a conflicting route and into the path of another high speed train.

Call-on control.—If, as assumed, the signal Z^2 , representative of a stop-and-stay signal, is also a semi-automatic signal, that is, is controlled by track circuits as well as manually by a lever man, then this signal may be at stop due to the presence of a train ahead 100 in the next block or within the automatic control limits for this signal. Ordinarily, the indication of this signal Z^2 and the automatic train control enforced in conjunction therewith would be the same whether 105 this signal were at stop due to manual control or due to the presence of another train ahead; but, while a manual control signal should bring about an absolute stop, under certain circumstances it may be desirable to 110 allow a train to proceed by this signal at stop when such stop indication is due to the presence of another train ahead. For example, it may be desired to advance the 115 train at the signal Z^2 to receive a clearance 120 card, pull up to a station, platform, or take a subsidiary route. These matters are well recognized in the art, and are commonly taken care of by the use of a so-called call-on signal. It is a characteristic of the present 125 invention that it may be used in conjunction with the regular call-on signal, as diagrammatically and conventionally shown.

Assuming that the tower man wishes to 130 advance a train past the signal Z^2 at stop,

after having placed his lever 53 in the reverse or clear position shown in full lines, this being possible of course if there is no conflicting route set up, the operator closes 5 the push button 67, thereby supplying simplex circuit current to the short section just ahead of the signal Z² and likewise closing the clearing circuit for the call-on signal 59. The train may now advance at the minimum speed by the signal Z² without receiving an automatic brake application.

If the lever in the tower is in the normal or stop position (dotted) to permit a second train to take a conflicting route, the energizing circuit for the line relay 40 is broken and further the circuit for the call-on signal 59 and the auxiliary circuit for supplying simplex current between the signal Z² and the end of the block can not be completed, 15 so that the pressing of the call-on push button 67 does not operate the call-on signal or energize the simplex circuit mentioned when a conflicting route is set up. In other words, the call-on push button 67 permits the clearing 20 of the call-on signal 59 and the removal of the absolute stop restriction by the train control apparatus when the block K is occupied, but does not permit such control when a conflicting route is set up.

Attention is directed to the construction 25 of the contacts operated by the relays 4 and 4¹ and corresponding contacts on the line relay 40. These contacts are of the make-before-break type, and the upper two contacts used for transferring the track or loop circuit feed from one end to the other of the second section of a block are preferably adjusted so as to make one circuit before the other circuit is broken, thereby maintaining current on this section at all times; whereas 30 the lower two contacts used for reversing the direction of current flow in the first section of the block are adjusted very closely but not close enough to make both circuits simultaneous. This close adjustment of the contacts of the make-before-break type, causes them to function like a snap circuit controller so as to make and break these circuits very quickly, so that a series of blocks 35 will not be momentarily affected. If desired, instead of the make-before-break contacts illustrated, double-throw snap circuit controllers operated by the signal or in any other suitable manner may be used.

In Fig. 2 directly below the block J have been illustrated curves 117, 116 and 118, similar to those shown under the block I illustrating the permissive, the actual and the apparent speed, respectively, of a train 40 when moving through the block J with its brakes applied. It should be noted that the apparent speed, as indicated by the device AG, may assume a negative value as shown at the point just before the train comes to a stop. This is possible because the de-

celerating factor may be in excess of the actual speed of the train; and since the apparent speed is equal to the actual speed minus the decelerating factor, the device may indicate a negative value and the contact strips 102, 103 and 104 extend far enough down so that an automatic brake application can not take place by reason of a negative indication by the combined speed and deceleration indicating device AG.

An automatic train control system has thus been provided which is of the continuous inductive type and manifests the exact condition of traffic ahead on the train at all times, so that the train is released of a restriction in the speed by reason of danger traffic conditions ahead as soon as these traffic conditions clear up. Restrictive speed limits are automatically set up in accordance with traffic conditions and the location of the train; but these speed limits may actually be exceeded within safe limits, provided the train is being decelerated at a predetermined rate, there being used a unitary device which depends for its operation on the deceleration and the speed of the train at any point, regardless of the grade on which the train is running or any other local factors. An absolute stop may be enforced at an interlocking point, which absolute stop may be removed only by the tower man, either by clearing the route or by operating the usual call-on signal.

Having thus shown and described several specific features of a single embodiment of the present invention, this having been done for the purpose of illustrating the nature of the invention rather than the scope thereof, it is desired to be understood that various changes, modifications and alterations may be made to adapt the invention to any particular one of the various types of signal and braking systems encountered in practice, without departing from the nature and scope of the invention.

What is desired to be secured by Letters Patent of the United States, is:—

1. In an automatic train control system, the combination of car-carried apparatus including a two-element three-position relay adapted to be controlled by current flowing in trackway circuits, and trackway apparatus including two distinct alternating current circuits having currents flowing therein which are preferably displaced 90 electrical degrees under clear traffic conditions, one of which comprises several sections employing the usual track circuit, means for changing the direction of the flow of current in one section of said track circuit and for changing the feed from the exit to the entrance end of another section of said track circuit, whereby during the progress of the train the car-carried relay may be energized in the normal direction, may be energized in the 125

reverse direction and may be deenergized by controlling the track circuits only.

2. In an automatic train control system, the combination of car-carried apparatus comprising, two influence receiving devices for detecting the flow of alternating current in two distinct trackway circuits, a two-element three-position relay having one element connected to one of said receiving devices and having the other element connected to the other receiving device, a single element relay connected to one of said receiving devices, and trackway apparatus including two distinct circuits having alternating currents flowing therein, one of which comprises the usual track circuit, said single element relay being maintained energized in response to current flowing in the other of said trackway circuits, means for controlling said track circuit to cause said two-element relay to be energized in a normal direction, in a reverse direction and to allow it to be deenergized without deenergizing said single element relay, whereby four distinct controls of continuous character are transmitted by two distinct trackway circuits.

3. Car-carried apparatus for automatic train control systems of the type in which alternating current in the usual track circuit and in another trackway circuit are employed to energize a three-position relay on the railway vehicle in a normal direction, in a reverse direction or allow it to be deenergized comprising, a three-position relay, a speed responsive device, means for setting up three different speed limits if said relay is energized in a normal direction, in a reverse direction or is deenergized, respectively; means for automatically applying the brakes if the speed of the vehicle exceeds the permissive speed, and a stop relay normally maintained energized by current flowing in said another trackway circuit which is deenergized causes an absolute stop by an application of the brakes regardless of the speed of the vehicle.

4. Car-carried apparatus for automatic train control systems of the type in which alternating current in the usual trackway circuits and in another trackway circuit are employed to energize a three-position relay on the railway vehicle comprising, a two-element three-position relay, a device for indicating an apparent speed value depending on the speed of the vehicle and the deceleration of the vehicle, means for setting up three different speed limits if said relay is energized in a normal direction, in a reverse direction, or is deenergized respectively, means for automatically applying the brakes if the apparent speed of the vehicle exceeds the permissive speed, and a stop relay normally maintained energized by current flowing in said another trackway cir-

cuit to which if deenergized causes an absolute stop by an application of the brakes regardless of the speed of the vehicle.

5. Car-carried apparatus for automatic train control systems of the continuous type comprising, a two-element three-position relay and a single element two-position relay, means for energizing one element of the three-position relay in response to alternating current flowing in the usual track circuit ahead of the train, and means for energizing the other element of said three-position relay and said single element relay in response to alternating current flowing in another trackway circuit, whereby the three-position relay may be energized in the normal position, in the reverse position, and may be deenergized in response to the direction of flow and the absence of current in the usual track current without deenergizing said single element relay, and whereby the single element relay is deenergized in response to absence of current in said another circuit.

6. Car-carried apparatus for automatic train control systems of the continuous inductive type comprising, inductive influence receiving means responsive to the flow of alternating current in the usual track circuit ahead of the train, another inductive influence receiving means adapted to respond to the flow of alternating current in another circuit, and means for giving four distinctive controlling conditions in response to the phase relation and the absence of one or the other of said trackway currents.

7. Car-carried apparatus for automatic train control systems of the continuous inductive type comprising, inductive influence receiving means responsive to the flow of alternating current in the usual track circuit ahead of the train, another inductive influence receiving means adapted to respond to the flow of alternating current in another circuit, and means controlled by said influence receiving means for effecting four different restrictions upon the movement of the vehicle in response to the phase relation and the absence of one or the other of said trackway currents.

8. Car-carried apparatus for automatic train control systems of the continuous inductive type comprising, inductive influence receiving means responsive to the flow of alternating current in the usual track circuit ahead of the train, another inductive influence receiving means adapted to respond to the flow of alternating current in another circuit, a combined speed and deceleration indicator for indicating the apparent speed consisting of the actual speed of the vehicle minus a decelerating component, a brake control device, and means governed in accordance with the phase relation of said currents and the absence of current in one of said cir-

cuits for actuating said brake control device when the apparent speed of the vehicle is excessive.

9. Car-carried apparatus for automatic train control systems comprising, a shaft driven by an axle of the vehicle, a mass associated with said shaft and rotated therewith, an indicator responsive to the centrifugal force minus the deceleration force acting upon said mass through said shaft, a brake control device acting on the usual air-brake system, and means governed in accordance with traffic conditions ahead and cooperating with said indicator for automatically actuating said brake control device if the vehicle is moving at excessive speed and is being improperly controlled.

10. Brake control apparatus acting upon the usual air-brake system of the vehicle for applying the brakes thereof when deenergized, means governed in accordance with traffic conditions ahead for maintaining said brake control apparatus energized, said last mentioned means also including a device having a mass rotated in accordance with the speed of the train, said device being responsive to the difference between the centrifugal force and the rotative decelerating force acting upon said mass, and means for deenergizing said brake control apparatus if said device indicates an excessive value, whereby the brakes are automatically applied if the speed is excessive for the particular traffic conditions existing ahead unless the train is being adequately decelerated.

11. Car-carried apparatus for automatic train control systems of the continuous inductive type comprising, inductive influence receiving means responsive to the flow of alternating current in the usual track circuit ahead of the train, another inductive influence receiving means adapted to respond to the flow of alternating current in another circuit, a brake control device acting on the usual air-brake system of the train for applying the brakes if deenergized, means governed in accordance with the flow of current in said trackway circuits including said receiving means for determining the limiting speed at which the vehicle may travel and which deenergizes said brake control device if the vehicle exceeds this limiting speed in response to absence of current in one of said trackway circuits, and which deenergizes the brake control device regardless of the speed of the train in response to the absence of current in both of said trackway circuits.

12. An automatic train control system of the continuous inductive type comprising, means for indicating the flow of alternating current in the usual track circuit ahead of the train, means partly on the vehicle and partly along the trackway for setting up a standard alternating current on a railway

vehicle with which the track circuit current may be compared to determine the phase relation of said track circuit current, a two-element relay on the vehicle having one element energized by said standard and having the other element energized in response to said track circuit current, a brake control device acting on the usual air-brake system of the vehicle which applies the brakes if deenergized, means governed by 70 said relay including a speed responsive device for deenergizing said brake control device if the vehicle exceeds predetermined speed limits depending upon whether said relay is energized in the normal direction, 75 in the reverse direction, or is deenergized, and vehicle carried means for deenergizing said brake control device regardless of the speed of the vehicle upon interruption of the supply of said standard alternating current. 80

13. Trackway apparatus for automatic train control systems for railways divided into blocks comprising, track rails divided by insulated joints into blocks having two sections also divided by insulated joints, means for applying simplex current consisting of current flowing in the two rails in multiple in each of said sections in automatic signal territory, means for supplying track circuit current to the exit end of the first section of a block of normal and reverse polarity when the block in advance is unoccupied and occupied respectively, means for supplying track circuit current to the exit end and the entrance end of the second section of each block of normal polarity when the block in advance is unoccupied and occupied respectively, and track relays governed by said track circuit currents. 95

14. Car-carried apparatus for automatic train control systems comprising, a normally energized brake control device acting on the usual air-brake system of the vehicle, means governed in accordance with traffic conditions ahead for deenergizing said brake control device if the speed of the train is dangerous and is not decreasing including a shaft rotated in accordance with the speed of the train, a mass associated with said shaft and rotating therewith, an indicator, and means for shifting said indicator in accordance with the centrifugal force and the rotative decelerating force 110 acting on said mass. 115

15. Trackway apparatus for automatic train control systems of the continuous inductive type operable in automatic signal and interlocking territory comprising, a partial simplex circuit including two track rails in multiple at the approach to interlocking territory, a semi-automatic stop-and-stay signal operated in accordance with traffic conditions ahead and in accordance 125 130

- with whether a conflicting route is set up and assuming an unfavorable indication condition if either traffic conditions ahead are dangerous or a conflicting route is set 5 up, means for energizing and deenergizing said partial simplex circuit under clear and danger indication conditions of said signal respectively, a normally inactive call-on signal, and means for independently energizing said partial simplex circuit and for placing said call-on signal in its active condition only operative if no conflicting route 10 has been set up.
16. Trackway apparatus for automatic train control systems of the type in which the usual track circuit current ahead of the train is detected to manifest on the train traffic conditions ahead of the train comprising, a section of track rails effectively 15 separated from the rest of the track by insulated joints, a track relay responsive to the potential across said rail, and means for supplying a potential across either end of said track rails, whereby if the source of 20 supply is connected to the exit end of said track rails the presence of current in the track rails is manifested on the train, and if the source of supply is connected to the entrance end the flow of current in the 25 track rails is not manifested on the train because the track current does not flow ahead of the front axle thereof, whereby the track relay always responds properly to the flow of track circuit current in said 30 relay, but the presence of track circuit current is detected on the train only when fed from one particular end of the section.
17. Trackway apparatus for automatic train control systems of the type in which the usual track circuit current ahead of the train is detected on the train to manifest on the train traffic conditions ahead of the train comprising, a trackway divided by 35 insulated joints into blocks each having two sections each provided with the usual track relay, means for supplying track circuit current on the two sections of a block of predetermined polarity under predetermined conditions, and means including said 40 first mentioned means for supplying current of reverse polarity to the first section and supplying current to the second section in a manner that it operates its corresponding track relay properly, but its 45 presence is not manifested on the train when the next block in advance is occupied.
18. Trackway apparatus for automatic train control systems of the type in which the usual track circuit current ahead of the train is detected on the train to manifest the 50 conditions of traffic ahead comprising, a trackway having a section divided by insulated joints, a track relay connected between the rails of said section, means for 55 supplying current to the exit and entrance 60 end of said section when traffic conditions ahead are clear and dangerous respectively, whereby the track relay will function properly regardless of whether the current is supplied from the exit or the entrance end 65 of said section, and whereby the presence of current in the track rails is manifested on the train only if the current is supplied to the exit end of the section.
19. In an automatic train control system, 70 the combination of means partly on the vehicle and partly along the track and acting through an intervening air gap to transmit control influences to the vehicle in accordance with traffic conditions ahead, a normally inactive brake control device of the type which if once actuated remains in its active condition until restored, means for actuating said brake control device if the vehicle is not properly decelerated when 75 moving at a predetermined speed under predetermined traffic conditions ahead, and manually operable means for restoring said brake control device which inflicts a penalty 80 upon the engineer each time it is operated.
20. In an automatic train control and signaling system for railroads; the combination of means partly on the vehicle and partly along the trackway for transmitting control influences in automatic block territory corresponding to clear, caution or danger when traffic conditions ahead are clear, caution or danger, and effective to transmit influences corresponding to that of the usual call-on 85 signal at the approach of the train to an interlocking point in response to track conditions set up at such interlocking point; and cab signaling means responsive to such influences for giving cab indications in response to traffic conditions ahead in automatic block territory and to track conditions 90 set up at such interlocking point.
21. In an automatic train control and signaling system for railroads, the combination of means partly on the vehicle and partly along the trackway and effective during the progress of the vehicle along the trackway for transmitting control influences in automatic block territory corresponding to clear, caution or danger when traffic conditions 95 ahead are clear, caution or danger, and effective to transmit influences corresponding to that of the usual call-on signal at the approach of the train to an interlocking point in response to track conditions set up at such interlocking point; and cab signaling means responsive to such influences for giving cab indications in response to traffic conditions ahead in automatic block territory and to track conditions 100 set up at each interlocking point.
22. Car-carried apparatus for automatic train control systems of the continuous inductive type comprising, inductive influence receiving means responsive to the flow of 105
- 110
- 115
- 120
- 125
- 130

alternating current in the usual track circuit ahead of the train, another inductive influence receiving means adapted to respond to the flow of alternating current in another circuit, and means for giving four distinctive cab signal indications on the train in response to the phase relation and the absence of one or the other of said trackway currents.

- 10 23. In an automatic train control system, the combination of car-carried apparatus comprising a relay, amplifying means having its output circuit connected to said relay, coils carried by the vehicle directly in front of the first axles thereof connected so as to have voltages induced therein due to current flowing in one direction in one rail and in the other direction in the other rail cumulatively and connected to the input side 15 of said amplifying means, and trackway apparatus for effecting energization of said relay comprising, a section of track having a track relay connected across the rails thereof responsive to the current for effecting energization of the first mentioned relay, and means for applying current to either end of said section, whereby said track relay will respond to the presence or 20 absence of a train in said section and the

first mentioned relay can only detect current 30 in the trackway provided the train is headed toward the end from which said track section is fed and there is no other train ahead in that section.

24. In an automatic train control system, the combination of car-carried apparatus comprising a relay, amplifying means having its output circuit connected to said relay, coils carried by the vehicle directly in front of the first axles thereof connected so as to have voltages induced therein due to current flowing in one direction in one rail and in the other direction in the other rail cumulatively and connected to the input side 35 of said amplifying means, and trackway apparatus for effecting energization of said relay for a particular direction of movement of the train under predetermined traffic conditions comprising, an insulated section of trackway, and means controlled automatically in accordance with traffic conditions for applying current of a character capable of causing said relay to assume its energized position across the rails at one end or the other of said section. 40

In testimony whereof I hereby affix my signature.

OSCAR H. DICKE.
